UNITED STATES PATENT OFFICE

2,463,083

OVERLOAD RELEASED TOOLHOLDER

Dalmar T. Brownlee, Indianapolis, Ind., assignor
to Charles Drexler, Indianapolis, Ind.

Application August 11, 1947, Serial No. 767,879

6 Claims. (Cl. 279—51)

1

This invention relates to an overload releasing tool.

The invention may be embodied in a tap holder, a threading device, a torque wrench or a screw driver, for example by inserting in the collet a tap, a threading die, a nut socket or screw driver blade respectively.

Herein the invention is illustrated as of the tap holder type and is adapted for machine tapping. It eliminates tap breakage to a considerable extent, especially for small taps. Broken small taps are obviously expensive but more especially they are difficult to remove from the hole, the cost of removal frequently exceeding the tap cost.

Safety tap holders, in general use, are of the friction clutch type which require frequent adjustment to maintain the proper torque value.

The chief object of the present invention is to provide an overload releasing tool holder to avoid tool breakage and wherein the torque setting will be maintained for long periods of use without requiring adjustment.

One feature of the present invention resides in the provision of interchangeable shanks for such holder whereby the holder may be adapted for various machines.

Another feature of the invention resides in the combination clutch and the torque value maintaining mechanism included herein.

Still another object is to provide a dependable device for use in tapping blind holes in the softer metals such as cast iron and aluminum. In this case, the device is adjusted to release at a torque slightly in excess of that required to turn the tap. In the tapping machine, rotating in a forward direction, the tap is moved into the hole whereupon it threads its way to the bottom of the hole. Upon striking the bottom excess resistance to tap turning is set up, which causes the device to release and the tap to stop rotating. Reversal of the machine rotation then unscrews the tap out of the hole. By reason of maintenance of torque setting, this device may be used without danger of stripping the threads.

This device also may be used in connection with an automatic tapping machine with a set spindle travel for blind holes. In case a shallow hole is met with, the tap stops rotating upon striking the bottom hole and the collet holder spring relieves the end pressure until the spindle reverses rotation and unscrews the tap out of the hole, with no damage done.

This device is particularly suited for group tapping where a number of blind holes are tapped

2

simultaneously. The holes may be of different depths and the taps of different lengths, for if the machine is timed for the slowest tapping operation the other taps will have reached the bottoms of their respective holes and stopped, until reverse rotation occurs and unscrews all the taps out of their holes.

Other objects and features will be set forth more fully hereinafter.

10 The full nature of the invention will be understood from the accompanying drawings and the following description and claims:

In the drawings Fig. 1 is a longitudinal central section view of an overload releasable tool holder in socket form adapted for tap and like tool holding purposes, the shank being shown in elevation.

Fig. 2 is an elevational view of the shank adapter.

20 Fig. 2A is a similar view of a similar and smaller shank adapter.

Fig. 2B is a similar view of a similar and larger adapter.

Fig. 3 is an end view of any one of the aforesaid adapters.

Fig. 4 is an elevational view of the clutch spring etc.

Fig. 5 is a transverse section taken on line 5—5 of Fig. 1 and in the direction of the arrows.

30 Fig. 6 is a transverse section taken on line 6—6 of Fig. 1 and in the direction of the arrows.

Fig. 7 is a perspective view of the torsion spring.

In Figs. 1 and 2, 10 indicates the elongated body portion of a holder shank connected by 35 neck portion 11 to peripheral flange portion 12. This is connected at 13 to a spline type extension that has radial teeth 14 and a central bore 15.

In Fig. 2—A the similar or identical parts are designated by corresponding one hundred series 40 numerals. In Fig. 2—B the similar or identical parts are designated by the corresponding two hundred series of numerals.

Figs. 2, 2A and 2B illustrate but three interchangeable shank devices for the holder so that it can be adapted to any drilling, etc., machine.

A retainer 16 has at one end an inwardly directed flange 17 to engage flange 12, 112 or 212. Its other end is externally flanged at 18 and same is reduced at 19. This retainer is internally threaded as at 20 and the outer end is countersunk as at 21.

A tubular shell or housing 22 envelopes a sleeve 23 that has a reduced neck portion 24 internally splined as at 25 and externally threaded as at 26.

55 Thus the shank, the retainer and sleeve are

rigidly connected together although same may be detached for shank interchanging as desired or required.

The shell and sleeve are locked together by washer 21 and snap ring 28. Washer 21 mounts pin 29 which projects into a recess in the body to prevent the washer from rotating. The shell may include lubricant supply port 30 plugged as at 31.

When the sleeve of cast iron or semi-steel rotates in the housing of steel containing 1.5% manganese there results in the housing a glazed inner surface thus providing a very durable bearing.

Within the sleeve or pocket forming member is a clutch spring 32. It also is of 1.5% manganese steel and is slightly larger in external diameter than the confronting sleeve internal diameter so as to have light frictional contact therewith. This spring has several narrow turns (5) toward the energizing end and one rapidly widening turn at the opposite end. This end is where the pressure between the clutch spring and pocket, during clutching engagement, is by far the heaviest. This spring also attains a glazed finish. Such glazed finishes wear very slowly and retain consistent performance in months of use.

At the pressure end of and within said spring is disposed a clutch collar 33. This collar has a peripheral biased face 34 for facial contact with one end of the clutch spring. It includes a radial slot 35. It oppositely is arcuately cut away as at 36 and centrally disposed relative thereto is pin portion 37.

The shell or housing 22 is tapped at opposite sides as at 38 to take adjustable stops 39 that project inwardly into the arcuate recess 36 and are selectively engageable by pin 37 aforesaid.

In longitudinal alignment with collar 33 is a torsion spring 40 having a peripheral flight portion 41 thereon against which abuts the other end of said clutch spring. This spring has the bias face 42 on said flight and includes gap 43 adjacent which is a longitudinally coextensive tongue or key 44.

A shaft 45 is rotatably supported in the clutch collar 33 and substantially enveloped by torsion spring 40. The keyway 46 takes key 44 of said spring. The shaft includes groove 47 and takes snap ring 48 having a tongue 49 seatable in said keyway. A thrust washer 50 is interposed between the snap ring and shank as shown.

The adjacent end 51 of said shaft is reduced and is rotatably supported in bushing 52 press fitted into bore 53 of shank 10. The other end of said shaft is enlarged laterally at 53 and the periphery is splined as at 54.

The reduced extended tubular end 55 of housing 22 is correspondingly splined internally as at 56 so that shaft 45 can shift longitudinally thereof. The end thereof includes groove 57 taking snap ring 58. Adjacent the other end of the spline structure is groove 59 taking snap ring 60.

Slidably in the splined extension 55 is the collet holder 61 having external splines 62 and a central bore 63 confronting shaft 45. Therein is disposed a coil spring 64. The extended forward end of the collet holder is reduced as at 65 and externally threaded as at 66 to take the collet nut 67.

The collet includes jaws 68 and tubular end 69. This tubular end has a square bore 70 therethrough and externally includes a pair of diametrically disposed grooves 71 to take the in-

wardly directed diametrically disposed tongues 72 in the bore 73 of the collet holder aforesaid. The latter has tapered throat 75. The jaws 68 have a complementary exterior taper 76. These jaws form a square socket 77 which accommodates the tap or tool.

When the cap nut 67 is threaded upon threads 66 of the collet holder the latter is forced inwardly, the cap bearing upon the end faces of 10 the jaws. As the jaws move inward in the collet holder, the tapered or biased faces force the jaws radially inward for tool shank clamping. The tongue and grooves 72-71 insure tool, collet and collet holder unitization so far as rotation is concerned.

Since the collet holder is splined to the housing 22 at 62-56 the former assembly rotates with the housing and the latter rotates through the clutch with the shank adapter.

20 The operation may be briefly summarized as follows:

Power is applied to rotate the shank in a clockwise direction when looking at the shank end. The shank drives the pocket through the 25 spline connection. The pocket drives the clutch spring by frictional grip, friction being initiated at the narrow end, owing to the spring being a left hand helix. The wide end of the clutch spring applies torque to the wide end of the 30 flange of the torsion spring. The single internal spline of the torsion spring transfers torque to the shaft. The splines on the flanged end of the shaft transfer torque to the housing and finally to the collet holder, collet and tap or tool as 35 described.

When the torque exceeds the predetermined amount, the torsion spring deflects in an unwinding direction which causes an angular lag of the shaft, housing and control collar with respect to the clutch spring and pocket. As the 40 energising end of the clutch spring is keyed to the control collar, this angular lag winds said end of the clutch spring to smaller diameter which suppresses its frictional grip. The clutch 45 spring, housing and tap now cease rotation.

When reverse rotation is applied to the shank, the pocket drives the clutch spring from the opposite end, the wide end now becoming the energizing end and the torque being transferred 50 from the narrow end to the control collar and thence to the housing and the tap or tool. In reverse rotation the torsion spring is bypassed and there is no overload release.

While the invention has been illustrated and 55 described in great detail in the drawings and foregoing description, the same is to be considered as illustrative and not restrictive in character.

The several modifications described herein as 60 well as others which will readily suggest themselves to persons skilled in this art, all are considered to be within the broad scope of the invention, reference being had to the appended claims.

65 The invention claimed is:

1. A reversibly rotatable tool holder having a power applying end member, a housing rotatable relative thereto, a tool supporting mechanism slidably longitudinally in said housing, a control collar, a torsion spring coaxial therewith, an internal shaft within both and connected to the torsion spring, a clutch spring helix concentrically associated with the collar and spring, a pocket member concentrically associated therewith, the latter being rotatable by the first men-

tioned member and connected to one end of the clutch spring, the other end of the clutch spring being connected to the control collar, said shaft, housing and mechanism having a spline connection therebetween.

2. A tool holder as defined by claim 1 wherein the pocket member terminates in a detachable retaining nut, the housing being relatively rotatable but substantially axially non-movable relatively, the power applying end member having a locking flange and a slidable relatively non-rotatable connection with the pocket member, said nut effecting detachable connection between the pocket member and power applying member for latter member substitution purposes.

3. A tool holder as defined by claim 1 wherein the shaft and first mentioned member have confronting adjacent ends, one being socketed and the other having an extension socket seatable for internal shaft support and alignment.

4. A tool holder as defined by claim 1 wherein the pocket member terminates in a detachable retaining nut, the housing being relatively rotatable but substantially axially non-movable relatively, the power applying end member having a locking flange and a slidable relatively non-rotatable connection with the pocket mem-

ber, said nut effecting detachable connection between the pocket member and power applying member for latter member substitution purposes and the shaft and first mentioned member have confronting adjacent ends, one being socketed and the other having an extension socket seatable for internal shaft support and alignment.

5. A tool holder as defined by claim 1 wherein the control collar is oscillatable within the housing and travel limit stops limit the extent of the relative oscillation therebetween.

10 6. A tool holder as defined by claim 5 wherein the stops are adjustable relative to each other for adjusting the initiation, extent and termination of the relative oscillation in opposite directions.
